UNITED STATES PATENT OFFICE.

CHARLES H. ROBERTSON, OF FREDERICK, MARYLAND.

MATCH-SAFE.

No. 906,292.

Specification of Letters Patent.

Patented Dec. 8, 1908.

Application filed March 4, 1908. Serial No. 419,212.

To all whom it may concern:

Be it known that I, CHARLES H. ROBERTSON, a citizen of the United States, residing at Frederick, in the county of Frederick and 5 State of Maryland, have invented new and useful Improvements in Match-Safes, of which the following is a specification.

This invention relates to match safes and has for its object to provide a match safe in 10 which the matches are contained in a series of compartments each embodying means for advancing the matches successively at a given point and means for ejecting the matches therefrom one at a time, the said 15 compartment being in the form of leaves jointed together and adapted to fold independently of each other to facilitate the filling of the match safe as a whole.

With the above and other objects in view, 20 the invention consists in the novel construction, combination and arrangement of parts which will hereinafter be fully described illustrated and claimed.

In the accompanying drawings:—Figure 1 25 is a front elevation of a match safe embodying the present invention. Fig. 2 is a side or edge elevation of the same. Fig. 3 is a longitudinal section through the match safe. Fig. 4 is also a longitudinal section through 30 the match safe showing the way in which the leaves fold. Fig. 5 is a detail bottom plan view of a fragment of the match safe, showing the hinges which connect the compartments or leaves.

The match safe contemplated in this invention comprises essentially a base or back 1, sides 2 and a plurality of leaves 3 which are connected together at their lower ends by a corresponding number of hinges 4 which 35 enables the leaves to fold relatively to and independently of each other in the manner illustrated in Fig. 4. In addition to the leaves 3, the match safe may be provided with a door or cover 5 which is hinged at one 40 edge to the outermost leaf 3, as shown in Figs. 1 and 3, the said cover being held in place, parallel to the back or base 1 by means of a latch bar 6 which is pivotally connected 45 at one end as shown at 7 to one of the sides 2 50 while the opposite end is notched to engage a pin or stud 8 on the opposite side of the safe,

the said latch bar serving to hold the cover in place as shown in Figs. 1, 2 and 3. The base or back 1 is preferably extended as shown at 9 and provided with a hole 10 55 adapting the same to be hung on a hook, nail or other support. Each of the leaves or sections 3 is provided at its outer free edge with a flange 11 provided with a guide opening for the sliding stem 12 of the follower 13 consisting of a bar adapted to rest on top of the matches carried by the leaf in the manner illustrated in Fig. 3, said follower acting to move the matches downward in order to position the lowermost match in readiness to be 60 acted upon by a match ejecting plunger 14 with which each one of the hinged leaves is provided. The plunger 14 operates through an opening in the one edge of the leaf with which it is associated and is normally held 70 downward or returned to its projecting position by means of a coil spring 10 which surrounds the stem and bears against the head or button 16 as shown in Fig. 1. The opposite side 2 of the match safe is provided with 75 holes 17 in line with the several plungers 14 through which the matches are ejected by the operation of the plungers, the latter being mounted upon and carried by the opposite side of the match safe and arranged directly 80 in line with the openings 17.

In order to fill the match safe, the leaves thereof are folded downward to a substantially horizontal position and the matches are then placed upon the upper and inner 85 sides of the leaves in single tiers as shown in Fig. 3. As the leaves are filled with matches they are folded one against the other as illustrated in Fig. 3, and after the match safe has been completely filled, the cover 5 is folded 90 against the outermost leaf by means of the latch bar 6. A match may be obtained by pressing inward any one of the plungers 14. As a match is re-drawn from the safe, the overlying matches are moved downward by 95 the action of the superimposed follower which acts by gravity. Should the follower fail to move, it may be pressed downward by bearing upon the proper guide stem 12.

I claim:—

1. A match safe comprising a base, a cover, means for fastening the cover, a plu-

rality of match holding leaves hinged together in book form between the base and cover, and an independent match ejector for each leaf.

- 5 2. A match safe comprising a plurality of connected match holding leaves hinged together in book form, a match ejector for each leaf, and a follower for each leaf operating to

advance the matches successively into the path of the ejector.

In testimony whereof I affix my signature in presence of two witnesses.

CHARLES H. ROBERTSON.
